UNITED STATES PATENT OFFICE.

HENRY AREGOOD, OF MANSFIELD TOWNSHIP, BURLINGTON COUNTY, NEW JERSEY, AND STEPHEN USTICK, OF PHILADELPHIA, PENNSYLVANIA, ASSIGNORS TO JNO. L. MAC-KNIGHT, OF BORDENTOWN, NEW JERSEY.

MACHINE FOR MAKING CLAY PIPES.

Specification of Letters Patent No. 24,174, dated May 24, 1859.

To all whom it may concern:

Be it known that we, HENRY AREGOOD, of Mansfield township, in Burlington county and State of New Jersey, and STEPHEN USTICK, of the city of Philadelphia and State of Pennsylvania, have invented a new and useful Machine for Making Clay Pipes for Hydraulic and other Purposes, and that the following is a full, clear, and exact description of the construction and operation of the same, reference being had to the accompanying drawings, in which—

Figure 1, is a top view of the machine. Fig. 2, is a side elevation of the same. Fig. 3, is a longitudinal section through the line X, X, of Fig. 1. Fig. 4 is a front view of the grate E. Fig. 5, is a top view of do. Fig. 6, is a front view of the die F'. Fig. 7, is a top view of the same. Fig. 8, is a perspective view of the core pin H. Fig. 9, is a front view of the cutter I.

Like letters in all the figures represent the same parts of the machine.

Our invention consists in certain improvements in machines for making bell end pipes.

To enable others skilled in the art to make and use our invention we will proceed to describe its construction and operation.

A, is the standing frame to which the several parts of the machine are attached.

A', is a continuation of frame A, which forasmuch as it does not have to sustain much weight is made much lighter than the frame A; and is made to detach from the said frame at pleasure for convenience in moving.

B, is the trough through which the clay is forced to form the pipes.

C, is the hopper which contains the prepared clay.

D, is a slide, in the bottom of the hopper C, which cuts off the communication between it and the trough B, while the pressing is performed it fits in appropriate grooves in the hopper, and in grooved pieces a, a, in the rear of the same.

E is a grate near the front end of the trough B, through which the clay is forced and thence in its passage through the die F', of plate F.

G is a mold for forming the outside of the bell end of the pipe—the said mold being

made in two pieces to open and close for the purposes that will be explained below. They have arms b, b, and b', b', which slide in grooved pieces c, c, in front of the main frame A.

H, is a core pin that gives shape and size to the inside of the bell end of the pipe. The inside end has a steady pin that fits in a hole in the center of the die plate F, and it has a ring q' which rests back of a rabbet of the mold G, to hold it in its longitudinal position while the bell end of the pipe is being formed.

I, is the cutter which cuts the pipe from the die at the termination of each forward stroke of the piston J.

K, is the driving shaft.

L, is a cam wheel on the driving shaft K, its rim L', running between the friction wheels g and h, in the rear end of the piston frame J.

M, is a cam wheel on the driving shaft K, whose rim M', running between friction wheels l and m, on the rear end of the shaft N, which slides in grooved piece c, operates the same, the front end of said shaft being connected by means of pins with the arms n, n', of rock shafts O, O', and the arms o, o and o', o' being connected by means of the pins p, p', with the slides b, b and b', b', of the mold G, the requisite motions and positions are given to both halves of said mold as will be hereafter described.

Q, is a cam strip on the reverse side of the cam wheel L, and is represented by red lines in Fig. 2. Its office is to give a reciprocating motion to the slide D, to which the front end of the rod R is attached. The rear end of the said rod slides in the grooved piece y. The said cam strip Q, runs between the friction wheels Z, Z', which are situated on the rear end of rod R.

S, is the driving pulley situated on the shaft K. In Fig. 3, it is represented by red lines.

The groove U, in the inner side of the driving pulley S, and which in Fig. 3 is shown in red lines operate the rock shaft T, and thence the knife I, the latter being used to cut the pipe off, and form its connection with the die F', the arm v, of said rock shaft being connected with the said groove

U, by means of the friction wheel u , and the arm w , with the cutter I by means of the pin X.

The endless apron V, encircles the series 5 of rollers a' , a' , a' , &c. and is made to run freely therewith to carry forward the pipe as it is formed.

The operation of the machine is as follows: Power being communicated to the 10 driving pulley S, by means of steam or otherwise it causes the driving shaft K, to revolve with the cam wheels attached thereto in the direction of the arrow. And as the outer periphery e , of the rim L', of the 15 cam wheel L, from the point 1, to the point 2, passes the friction wheel g , of the piston frame J, said segmental portion being an eccentric curve, the point 2 being farther from the center of the driving shaft K, than the point 1, the piston is moved 20 forward in the trough B, and forces the clay through the die F' into the mold G, and fills the same and thus forms the bell end of the pipe. The piston is then allowed 25 to remain stationary while the said outer periphery e , of the rim L', from the point 2 to the point 3 passes the friction wheel g , said portion of the rim being a concentric curve scribed from the center of the driving 30 shaft K. During which time the outer periphery j of the rim M', of the cam wheel M, from the point 1 to the point 2 has passed the friction wheel l , on the shaft N, and said portion of the rim being an eccentric curve the point 2, being farther from the center of the driving shaft K, than the point 1, the said shaft is forced forward 35 moving the arms n , n' , of the rock shafts O, O', forward and consequently the arms 40 o , o , upward and the arms o' , o' , downward, and thus spreading the upper and lower parts of the mold G, apart to allow the belt end of the pipe just formed, and the core pin H to pass freely out of the 45 same. The halves of the mold G, are held in said position while the outer periphery j from the point 2, to the point 3, which is a concentric curve, scribed from the center of the driving shaft K, passes the said friction 50 wheel l . The inner periphery k , of the rim M', of the cam wheel M, from the point 1, to the point 3, has no office to perform and is made parallel with the outer periphery between said points to freely 55 pass the friction wheel m , on the shaft N. The outer periphery e , of the rim L', of the cam wheel L, from the point 3, to the point 4 is an eccentric curve, the point 4, being farther from the center of the driving 60 shaft K, than the point 3, and as it passes the friction wheel g , it forces the piston J, forward and presses the clay in the trough B, through the die F', and forms the small, or straight part of the pipe, the bell end in the meantime advancing for-

ward and the bottom side of foot of the core pin H, resting on the apron V, and sliding over the rollers a' , a' , a' , a' , &c., to prevent the pipe touching the same. The pipe being thus formed it is cut off from 70 the die F' by means of the cutter I, as follows. The groove U, in the side of the driving wheel S, from the point 1, to the point 2, being an eccentric curve operating on the friction wheel u , on the arm v , of 75 rock shaft T, forces the said arm upward and arm w downward which carrying the cutter I, with it causes the latter to cut the pipe off. A reversed motion is then given to the knife I, carrying it back to its place 80 with its cutting edge around the die F', by means of the counter eccentricity of the groove U, from the point 2, to the point 3. The knife is then held in its place while the groove U, from the point 3, to the point 85 1 passes the friction wheel u , that part of the groove being a concentric curve scribed from the center of the driving shaft K. The pressing of the clay in the formation 90 of the pipe having terminated when the point 4 of the outer periphery e , of the rim L', of the cam wheel L, has reached the friction wheel g' , and the point 4 of the inner periphery f , has reached the friction 95 wheel h , of the piston frame J, the said inner periphery f , takes a rapid turn inward, toward the center of the driving shaft K, from the said point to the point 100 5, and forces the piston frame J, backward with the front end of the piston to the rear side of the hopper C. During the backward motion thus described of the piston J, the slide D, in the bottom of the hopper C, is made to recede with its front end even with the rear side of the hopper to 105 allow the clay in the same to descend into, and fill the trough B, said backward motion of the slide D, being given by the outer periphery b' of the cam strip Q, from the point 1, to the point 2, pressing against the friction wheel Z, on the rear end of the rod R, said portion of the periphery being an eccentric curve, the point 2, being farther from the center of the driving shaft K, than the point 1. The said outer periphery 110 b' , then assumes a concentric curve from the point 2, to the point 3, to keep the slide D, stationary a short time to allow the clay time to descend from the hopper C, into the trough B. The inner periphery c' , then takes a rapid turn inward toward the center of the driving shaft K, the point 115 4 being nearer the center of the said shaft than the point 3, and bearing against the friction wheel Z', forces the slide D, forward with its front end touching the front side of the hopper C, and thus to prevent the clay passing out of the trough B, except through the die F', the continuation 120 of the said inner periphery of the strip Q,

from the point 4, to the point 5, is a concentric curve scribed from the center of the driving shaft K, and by impinging on the friction wheel Z', prevents the slide D, 5 rebounding. During the forward motion thus described of the slide D, the piston J, has been held stationary by the inner and outer peripheries *e* and *f* of the rim L' of the cam wheel L assuming a concentric 10 curve from the point 5, to the point 1, the place of beginning.

All the motions which are necessary to the formation of a single pipe have been described in one revolution of the driving 15 shaft K. By multiplying the revolutions of the shaft, the number of the pipes will be multiplied accordingly. As the core pin H, has to be inserted in its place within the mold G, before the closing of the 2 halves 20 of the latter, we design having several of the same size, in order to secure certainty of one or more being in reach of the person attending the machine at all times.

We purpose using the above described 25 machine for making straight pipes and draining tile, in which case we detach the mold G, and core pin H, and their connections.

Having thus fully described our improvement 30 we do not purpose to claim the mold, core pin, or knife or cutter, as these devices are employed in the machine patented by C. P. Wardwell April 21, 1857, but are there operated in combination with levers 35 by a different arrangement of parts and by gearing, but

What we do claim as our invention and desire to secure by Letters Patent is—

1. The annular ring *g'*, upon the core pin H, (which is also provided with a foot) in 40 combination with a flange upon the inside of the outer front end of the mold G, to retain the core pin in place while forming the bell end of the pipe operated in the manner and for the purposes specified. 45

2. The cam wheel L, in combination with the piston J, trough B, and its connections, mold G, and core pin H, for making the bell end and straight part of the pipe at one 50 operation.

3. The combination of the rock shafts O and O', with the 2 halves of the mold G, the former being operated by the cam wheel M, and shaft N, for the purposes above 55 described.

4. The slide D, rod R, and cam strip Q, arranged as described for the purpose above set forth.

5. The arrangement and combination of the cam U, rock shaft T, and levers W, and 60 *v*, for operating the knife I in the manner and for the purpose specified.

In testimony that the above is our invention we have hereunto set our hands and affixed our seals this nineteenth day of 65 February, 1859.
